UNITED STATES PATENT OFFICE

LEWIS LARSEN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS

METHOD OF MAKING COMBINED CLOSELY WOVEN AND FITCH WORK FABRIC

Application filed December 28, 1928. Serial No. 328,894.

This invention relates to improvements in methods of making combined closely woven and fitch work fabric and it consists of the matters hereinafter described and more particularly pointed out in the appended claims.

Such a fabric is extensively employed in the furniture industry as the covering or body of the frames of many different articles such as chairs and the like and has been woven directly upon the frames of said articles. The weaving of such fabric in this manner is slow and exacting and can only be performed by artisans long experienced with the characteristics of the material employed.

15 The fabric with which the present invention is concerned comprises a part of closely woven over and under stake and strand fabric and another part of more open character known as fitch work so that the forming or 20 building up of such a fabric upon an article frame calls for an artisan.

The fabric herein includes a plurality of laterally spaced members called "stakes" which may be either of reed, reed fibre or 25 fibre having a wire core and which in workable lengths have sufficient rigidity to be self supporting but may be flexed or bent when necessary to position them in the relation desired in the finished fabric.

30 Upon the "stakes" certain members called "filler" and "fitching" strands are woven and twisted to hold the stakes in the desired arrangement. The filler and fitching strands may be of a diameter greater or less than 35 that of the stakes and are of such character that they may be readily laid in and twisted about the stakes.

In the closely woven part of the fabric, the stakes are substantially parallel and the 40 filler strands are laid in, over one stake and under the other, with the several courses of strands disposed in close relation. Instead of each course comprising a single or individual strand, a double or twin strand may 45 be employed. In the more open woven part of the fabric, the stakes may be disposed in several different ways, that is in some portions they may be parallel and in others they may be arranged to cross each other. Again 50 all of the stakes in the more open part of

the fabric may be arranged to cross and re-cross each other to provide an open diamond effect, the fitching strands being twisted in along desired lines and acting to hold the stakes in the desired relation.

When the stakes and strands are of fibre reed which is composed of twisted paper, the paper while in strip form may be conveniently dyed the desired color and this eliminates the necessity of painting or coloring the finished fabric and at the same time provides for a novel variety of pleasing color effects.

The operation of manipulating and holding the stakes with one hand and laying in the strands with the other and in the meanwhile, shaping the fabric to the frame as the fabric progresses, is indeed difficult and requires skilled artisans. It is a slow and laborious operation at the best so that only 65 workmen with long experience can be employed for this kind of work and even then the time required to produce a relatively small article is considerable. Therefore, articles of furniture having this kind of frame 70 covering or fabric are quite expensive.

The general object of the present invention is to provide a novel method of producing a fabric of this kind, ready for application to an article frame whereby the finished 75 article may be made in less time and at a lower cost.

Another object of the invention is to provide a method which may be carried out by unskilled workers with an assurance of uniformity in the fabric produced.

Still another object of the invention is to provide such a method as is practical for use in factory systems of making the fabric apart from but to conform to the frame and thereafter applying the fabric to such a frame to produce the finished article.

The invention consists generally in the steps and acts as well as in the sequences in which they are carried out, whereby the above mentioned objects as well as others as will hereinafter appear, are obtainable and my invention will be more readily understood by reference to the accompanying 100

drawings illustrative thereof and wherein:—
Fig. 1 is a plan view of a portion of the fabric which may or may not have been woven on a loom and with portions of the stakes projecting beyond opposite edges thereof, ready for subsequent steps of the improved method to be carried out thereon.

Fig. 2 is a plan view of one end of the fabric after it has been trimmed to the desired angularity and has been bound to prevent its ravelling.

Fig. 3 is a plan view of the trimmed and bound fabric portion of Figs. 1 and 2 after the first line ofitching has been laid in place along one edge thereof.

Fig. 4 is a detail sectional view on an enlarged scale through one bound margin of the fabric, the plane of the section being taken on the line 4—4 of Fig. 2.

Fig. 5 is a plan view showing the fabric thus far formed, in position upon one section of a templet and distorted in an edge-wise plane and with portions of the projecting stakes at one edge of the fabric crossed in accordance with suitable sets of guiding means thereon and with a second line of strands fitched in place along a predetermined line.

Fig. 6 is a view similar to Fig. 5 after another templet section has been brought into operative position with the first and the stakes have been arranged in accordance with other guiding means on the second section and a third line of strands has been fitched in place along a predetermined line.

Fig. 7 is a top plan view of a portion of the finished fabric when removed from the templet and ready for application to the associated frame for which it is intended.

Fig. 8 is a perspective sectional view showing a part of the templet when the two sections thereof are in operative relation.

In carrying out the improved method I first make up a piece of stake and strand fabric of a predetermined size and comprising a plurality of laterally spaced, substantially parallel stakes 1—1 of suitable length, upon which are woven the desired number of closely adjacent strands 2—2, each in alternation over one stake and under the next to provide a band or area 3 of closely woven fabric of proper length and width. The weaving of so much of the fabric may be done either by hand or by means of a suitable machine or loom but in either case the stakes are of a length greater than the width of said band or area so as to extend beyond each longitudinal edge thereof to leave top and bottom stake extensions 4 and 5, the terms "top and bottom" being relatively only and employed for the sake of convenience in designating the positions said extensions occupy in the making up of the fabric as a whole.

In the drawings I have shown the stake

extensions 4 as duplex or double in form instead of single as are the stake extensions 5 although this duplex arrangement could be provided for both sets of stake extensions if so desired. To provide such a duplex arrangement for the stake extensions I simply add another stake member 4^a of shorter length for each of such extensions and which stake member is bound or anchored in place along side of its associated extension by those strands 2—2 in the top portion of the band or area 3.

After such a fabric band has been thus formed its ends are trimmed off at the desired converging angles which trimmed ends are then bound with a metallic binder strip 6 best shown in Fig. 2 to there prevent the ravelling of the fabric. While the fabric band is in this condition, I weave or lay in the first line ofitching 7 upon the duplex stake extensions 4—4^a. Said line ofitching comprises two strand members 7^a and 7^b respectively and the strand member 7^a at the front of one stake is twisted over the strand member 7^b to the rear of said stake which is then brought to the front of the next stake and so on, the strand member at the front of the stake always being twisted over and about the strand member at the rear of the stake so that said strand members cross each other between the stakes.

This manner ofitching in the strand members requires less hand movements upon the part of the fitcher and may be carried out more rapidly than was heretofore possible, when the strand member to the front of one stake was twisted under the strand member to the rear of said stake member. The fitching strand is then worked down on the stakes into engagement with the first course of filler strands 2 on the fabric band 3 and the ends of said fitching strands are then twisted together as shown to prevent their ravelling.

The necessary steps to complete the fabric are carried out in connection with a templet upon which the thus far formed fabric is placed. Such a templet which is best shown in Fig. 6 comprises a main section 8 and a secondary section 9 adapted to be brought into operative position with respect to the main section when so desired, the templet of course being placed or supported upon a suitable bench or the like (not shown) when in actual use by the workman.

The main templet section 8 is of an area greater than that of the closely woven fabric band 3 and is curved along its top edge 10 in accordance with a predetermined line desired to be given to the second line ofitching in the fabric. Along said top edge 10 of the main section of the templet is provided a row of longitudinally spaced guide pins 11 and along the bottom edge of the main section is provided a plurality of stop

pins 12 disposed on an arc or curved substantially concentric or parallel with the row of guide pin 11.

To apply the partly completed fabric to the main templet section, the longer edge 13 of the fabric which is substantially straight, is engaged against the endmost stop pins 12 on said templet section and the mid portion of said partly completed fabric 10 is worked or distorted in the plane of weave down toward the intermediate pins 12 so that the fabric is curved in accordance with said stop pins 12 and top edge 10 as best shown in Fig. 5. Each alternate duplex 15 stake extension 4-4^a is then flexed to the right to engage against the right hand side of the proper pin 11 and then each intermediate duplex stake extension 4-4^a is flexed to the left to engage against the left hand 20 side of the proper pin 11 so that the stakes cross each other to provide an area 14 of open diamond weave or mesh as best shown in Fig. 5. I then manipulate another pair 25 of strands upon the stake ends to form a line ofitching 15 following the contour of the edge 10 of the main templet section.

The main templet section and the secondary templet section are preferably made of wood and the secondary section which is 30 much narrower than the main section has top and bottom edges curved to conform to the top edge of the main section. The secondary section is operatively connected to the main section by a pair of hinges 16 35 located on the under side of the templet near the middle thereof. On the underside of each end of the main section near its top curved edge is provided a pivoted latch plate 17. When the secondary section is 40 swung about the hinges 16 into the plane of the main section, the latch plates 17 are turned so that one end thereof projects under the secondary section and holds the same in place.

45 The secondary templet is provided with a row of longitudinally spaced guide pins 18 as best shown in Fig. 6 and those parts of the duplex stake extensions 4-4^a beyond the line ofitching 15 are engaged behind the 50 proper pins 18 to provide another area 19 of open diamond weave or mesh upon the secondary section. Another pair of strands is fitted in place upon those portions of said duplex stake extensions beyond the 55 top edge of the secondary section to provide a line ofitching 20 conforming to said edge and said duplex stake extensions are trimmed off parallel with but spaced from said edge to provide ends 21 adapted to be 60 secured to the corresponding portion of an article frame in any convenient manner.

The thus far formed fabric is removed 5 from the templet and the stake extensions along the other longitudinal edge of the 65 fabric are then turned down and inter-

twined with each other to form a border 22 for the fabric which is now ready for attachment to the article frame for which it was originally intended.

It is apparent that as the duplex stake 70 portions are disposed in the desired relation and theitching strands are then applied, they are tied or connected together in said relation and theitch work portion of the fabric acts to hold the closely woven portion 75 of the fabric in the position into which it has been distorted.

From the above, it is apparent that a pre-formed fabric is provided which includes a closely woven part and a more open woven anditching part, the shape or outline of which is of course dependent upon the shape necessary to fit the associated frame. Thus under this method by providing the necessary templet, combined close woven anditching fabric for a great variety of articles 80 may be produced with speed and uniformity by unskilled workers at a relatively low cost.

In qualifying the fabric or its elements as reed in the specification and claims, I, of course, mean such elements as cooperate in the manner above described and have the characteristics of stakes and strands such as are now employed in the reed industry and also to include such materials as natural 90 reed and paper reed.

In Figs. 5, 6 and 7 of the drawings, I have omitted the central portions of the area 3 of closely woven stake and strand fabric, solely for the purpose of simplicity, in illustrating the invention and it is to be understood that such omitted portions do not constitute openings in said area of such fabric.

Inasmuch as the disclosure herein will readily suggest to others skilled in the art to which this invention appertains, various methods and templets whereby the substantial objects of the invention can be attained, I do not wish to be limited to the specific stated manner of procedure nor to the precise steps, acts or sequences thereof except only as may be necessary by limitations in the appended claims.

I claim as my invention:—

1. The method of making a fabric of the kind described which consists in providing a piece of substantially close woven stake and strand fabric material having stake portions projecting beyond one edge thereof, then placing said material upon a templet having stake guiding means thereon, deflecting the projecting stake portions substantially in the plane of the material and engaging them with the desired guiding means and thenitching in strands upon said deflected projecting stake portions along the desired line thereon to form a combined close woven stake and strand anditching fabric.

2. The method of making a fabric of the

kind described which consists in providing a piece of substantially close woven stake and strand fabric material having stake portions projecting beyond one edge thereof, 5 in providing a templet having stake guiding means and fabric curvature defining means, placing said material upon said templet and distorting it in the plane of the weave to conform the other edge of the material to the fabric curvature defining means, deflecting the projecting stake portions substantially in the plane of the material and 10 engaging said deflected stake portions with said stake guiding means and thenitching in strands upon said deflected projecting stake portions along the desired line.

3. The method of making a fabric of the kind described which consists in providing a piece of substantially close woven stake 20 and strand fabric material having a set of stake portions projecting beyond opposite edges thereof, initching in strands upon one set of stakes along one of said edges, in providing a templet having stake guiding means and fabric curvature defining means, placing said material upon said templet and 25 distorting it in the plane of the weave to conform the other edge of the material to the curvature defining means deflecting the first mentioned set of stake portions in substantially the plane of the material and engaging them with said stake guiding means, initching in strands upon said first mentioned set of deflected projecting stake portions beyond said stake guiding means and 30 then turning down the other set of projecting stake portions to form a border therefor.

4. The method of making a fabric of the kind described which consists in providing a piece of substantially close woven stake 40 and strand fabric material having stake portions projecting beyond one edge thereof, in providing a templet comprising a main section and a second section adapted to be oper- 45 atively positioned with respect to the main section and each having stake guiding means thereon, positioning the material upon the main section, deflecting the projecting stake portions substantially in the plane of the material and engaging them with the guiding means on the main section, 50itching in strands upon those stake portions beyond the main section, bringing the second section into operative relation with respect to the main section, further deflecting said projecting stake portions and engaging them with the guiding means on the second section and thenitching in strands upon said deflected stake portions beyond the guiding 55 means on said second section.

5. The method of making a fabric of the kind described which consists in providing a piece of substantially close woven stake and strand fabric material having stake portions 60 projecting beyond one edge thereof, in pro-

viding a templet comprising a main section and a second section adapted to be operatively positioned with respect to the main section and each having stake guiding means thereon, said main section also having fabric curvature guiding means, placing the material upon the main section and distorting the material in the plane of weave in accordance with said fabric curvature guiding means, deflecting the projecting stake portions in substantially the plane of said material and engaging them with the guiding means on the main section,itching in strands upon those stake portions beyond the main section, bringing the second section into operative position with respect to the main section, further deflecting said projecting stake portions and engaging them with the guiding means on the second section, 70 thenitching in strands upon said stake portions beyond the guiding means on said second section.

6. The method of making a fabric of the kind described which consists in providing a piece of substantially close woven stake and strand fabric material having a set of stake portions projecting beyond opposite edges thereof,itching in strands upon one set of stakes along one of said edges, in providing a templet comprising a main section and a second section adapted to be operatively positioned with respect to the main section, each of which have stake guiding means therein, the main section also having fabric curvature guiding means, positioning the material upon the main section and distorting the material out of the plane of weave until one of said edges engages with and conforms to said fabric curvature guiding means, deflecting the stake portions projecting from the opposite edge in substantially the plane of the material and engaging them with the stake guiding means on the main section, laying initching strands upon said stake portions beyond said guiding means, bringing the second section into operative position with respect to the main section, further deflecting said stake portions and engaging them with the guiding means on the second section, laying in another line ofitching strands upon said stake portions, beyond said second section, removing the fitted fabric material from the templet and turning down the other set of stakes to form a border therefor.

7. The method of making a fabric of the kind described which consists in providing a piece of closely woven stake and strand fabric material with the stakes extending substantially at a right angle to the filler strands and with the stakes projecting beyond one edge of said fabric material, distorting the fabric in the plane of weave, disposing the projecting stake portions in the desired relation anditching in strands upon

said projecting stake portions, and thereby holding the fabric in its distorted condition.

8. A fabric of the kind described comprising a body portion of closely woven stake and strand fabric material distorted from its initially formed condition and an open fitch work portion extending therefrom and serving to hold the closely woven body portion in its distorted condition.

10 In testimony whereof, I have hereunto set my hand, this 20th day of December, 1928.

LEWIS LARSEN.
